(57) **CLAIM**

The ornamental design for a swimming gear hanger, as shown and described.

DESCRIPTION

FIG. 1 is an exploded perspective view of a swimming gear hanger of the present invention.

FIG. 2 is an exploded front view of FIG. 1.

FIG. 3 is an exploded rear view of FIG. 1.

FIG. 4 is an exploded left side view of FIG. 1.

FIG. 5 is an exploded right side view of FIG. 1.

FIG. 6 is a top view of the swimming gear hanger.

FIG. 7 is a bottom view thereof.

FIG. 8 is a perspective view thereof; and,

FIG. 9 is a front view thereof shown in use.

The broken lines shown in FIG. 9 are for illustrative purposes only and form no part of the claimed design.
